United States Patent Office

Des. 210,779
Patented Apr. 16, 1968

210,779

SPEAKER BAFFLE

Aston L. Moore, 220 Hammond Place,
South Bend, Ind. 46601

Filed Nov. 1, 1967, Ser. No. 9,239

Term of patent 14 years

(Cl. D26—14)

FIG. 1

FIG. 3

FIG. 4

FIG. 2

FIGURE 1 is a top perspective view of a speaker baffle showing my new design;

FIGURE 2 is a top plan view thereof;

FIGURE 3 is a sectional view thereof taken along the line III—III in FIGURE 2; and

FIGURE 4 is a bottom plan view thereof as seen from the cutting line IV—IV in FIGURE 3.

The dominant features of my design are shown in solid lines.

I claim:

The ornamental design for a speaker baffle, as shown and described.
